UNITED STATES PATENT OFFICE.

JAMES CASSIDY, OF CHICAGO, ILLINOIS.

TRACK-SANDING DEVICE.

1,148,829.

Specification of Letters Patent.

Patented Aug. 3, 1915.

Application filed October 17, 1914. Serial No. 867,175.

To all whom it may concern:

Be it known that I, JAMES CASSIDY, a citizen of the United States, and a resident of Chicago, in the county of Cook and State 5 of Illinois, have invented certain new and useful Improvements in Track-Sanding Devices, of which the following is a specification.

This invention relates to a sanding device 10 which is installed on motor and other cars, for the purpose of sanding the track on which said cars are propelled.

The objects of the invention are to obtain a sanding device by means of which the 15 tracks can be sanded before one or more of the wheels of the car, when the car is moving forward, at the will of the operator of the device; and a device by means of which the track can be sanded to the rear of 20 certain and determined ones of the wheels of said car.

A further object is to obtain a device of the kind named which is operative at either end of the car on which the device is installed.

Further objects are to obtain a device which is not liable to get out of order, or be broken; which is economically made, and is simple in construction.

To those familiar with the operation of electric motor cars it is known that at times it is desirable to discharge sand in front of but one pair of the wheels of the car; at other times it is desirable to discharge 35 sand in front of more than one pair of said wheels; and at times it is desirable, to prevent the car from slipping down a grade, or to move with certainty down said grade, to discharge to the rear of one or more of said 40 pair of wheels.

I have illustrated a device embodying this invention in the drawings accompanying and forming a part of this specification, in which—

Figure 1 is a side elevation of a car with the device installed therein, the upper part of the car being removed. Fig. 2 is a diagrammatic view of the device and of a portion 45 of a car. Fig. 3 is a top plan view of the axles and wheels of a car with this device in place thereto. Fig. 4 is a view on line 4—4 of Fig. 5, viewed in the direction indicated by the arrows. Fig. 5 is a section view on line 5—5 of Fig. 4, viewed in the direction indicated by the arrows. Fig. 6 is a side elevation of the valve and adjacent

parts of the device. Fig. 7 is a vertical section of the lower end of the vertical shaft and tube shafts by means of which the device is actuated. And Fig. 8 is a side elevation of a modification of location of the valve and adjacent pipes. Figs. 4, 5, 6 and 7 are on an enlarged scale.

A reference character applied to a given part indicates said part throughout the several figures of the drawings, wherever the same are illustrated.

X is the floor of a car.

Y, y, are the wheels of said car.

Z are the side beams, and Z¹ the side 70 beams of the platform of the car.

A is a vertical shaft, and a, (Fig. 3) are handles by means of which said shaft is actuated.

B is a vertical tube, which is mounted on 75 shaft A, to turn with or independently of said shaft.

C is an additional vertical tube, mounted on tube B, to turn with or independently of tube B and shaft A. Handle a is arranged, to actuate either or both of the tubes B and C with the shaft A, or to actuate shaft A only, as desired, by a construction which forms no part of this invention.

D is a chain wheel which is rigidly secured on shaft A, at the lower end thereof, E is a like wheel on tube B and F, F¹, like wheels on tube C.

G, H, I, and J, respectively, are sand boxes.

K, L, M and N are valves to said sand boxes, respectively, and k, l, m and n are the levers by means of which said valves are actuated.

O are springs which yieldingly hold the 95 several valves K, L, M and N in a normal and closed position.

g, h, i and j are sand pipes to direct sand flowing through the valves with which they are respectively attached to the track on 100 which wheels Y, y rest.

P, Q, R and S are rock shafts which are mounted underneath the floor of the car.

T are arms which are rigidly secured to shafts P, Q, R and S, respectively; and t 105 are additional arms which are also rigidly secured to said rock shafts, near the ends thereof.

U are links respectively connecting arms t with the levers k, l, m and n.

V, V¹, V², V³, are connecting chains and rods which are applied as follows:—Having

reference to Fig. 1, where said connections are shown from one platform only of the car, (to avoid confusion in said Fig.), a connection V is attached at one end to chain wheel D and at the other end to arm T of rock shaft P: a connection V¹ is attached at one end to chain wheel E and at the other end to arm T of rock shaft R: a connection, V² is attached at one end to chain wheel F and at the other end to arm T of rock shaft S: and a connection, V³, is attached at one end to wheel F¹, and at the other end to arm T of rock shaft Q. These connections are also well illustrated in Figs. 2 and 3, in addition to the like connections from the other platform of the car, which are—connection V attached to chain wheel D and arm T of shaft S: connection V¹, attached at one end to wheel E and at the other end to arm T of shaft Q: connection V², attached at one end to wheel F and at the other end to arm T of shaft P, and connection V³, attached at one end to wheel F¹ and at the other end to arm T of shaft R.

Assuming the right hand end of the car in Figs. 1, 2 and 3 to be the front end, when shaft A is turned, by means of handle *a*, the connection V will be moved longitudinally toward the right, and rock shaft P will be moved, to open valves K of sand boxes G, and sand will flow from said boxes G through said valves and through pipes *g* in front of wheels *y* which are adjacent to said pipe *g*; and this is the usual sanding required. If what I term an emergency sanding is required the shaft A and tube shaft B also are turned, by means of handle *a*, and in addition to the sanding of the track through the pipe *g*, the connection V¹ will be moved longitudinally, and valves M of sand boxes I will be opened and sand will flow through pipes *i* in front of wheels Y, which are adjacent to said pipes *i*. If the car be on a grade, or it is desired to back the car, and it is necessary to sand the track to the rear of some of the wheels thereof, the shaft A and tube shaft C are turned; and thereby in addition to sanding the track through pipe *g*, as hereinbefore described, connections V² and V³ will be moved longitudinally, the valves N and L will be opened, and sand will flow through the pipes *j* and *h* to the rear of wheels *y* (at the left hand end of the car) and wheels Y of the truck at the right hand end.

In Fig. 8 arm *t* is shown as extending down from rock shaft Q, to permit the valve L to be lowered, and sand box H to be placed below the floor X of the car. To make this arrangement it is simply necessary to place said rock shaft Q on the other side of the sand boxes H from which they are illustrated in Figs. 1, 2 and 3, and to place the sand box which is shown at the lower end of Fig. 3 on the upper end, and

the one on the upper end at the lower end; that is, to change said sand boxes to opposite sides of the car.

In placing this device on a car which already has sand boxes at the ends, and above the floor of the car the arrangement of levers, or arms, chain wheels, rock shafts P and S, thereto, and valves K and N will be preferably as illustrated in Figs. 1, 2 and 3, while the shafts Q and R may be actuated as is illustrated in Fig. 7, to permit the placing of sand boxes H and I below the floor X.

Whether the sand boxes be above or below the floor the shaft A and tube shafts B and C are unchanged, together with chain wheels D, E, F and F¹, with the connections V, V¹, V² and V³, thereto, respectively.

The several connections V, V¹, V² and V³ comprise a short length of chain at the ends thereof, respectively, so that the chain at one end may wind around its corresponding chain wheel, and movement of the arm T at the other end is permitted by the chain at said other end, when the chain wheel at said other end is turned.

I claim:

1. A car, provided with trucks, a plurality of axles in said trucks, and wheels on said axles, sand boxes, valves arranged to control the discharge of sand from said boxes, and guide spouts from said valves, in combination with rock shafts, connections between said rock shafts and said valves, separably movable vertical shafts at both ends of said car, and connections between all the shafts at both ends of said car and all of said rock shafts, whereby selected ones of said rock shafts may be operated from both ends of said car.

2. A car, a plurality of vertical shafts at each end of said car and a plurality of rock shafts to said car, in combination with longitudinally movable connections, means to attach one end of said connections to said vertical shafts at one end of said car and means to attach the other end of said connections to said rock shafts, additional longitudinally movable connections, means to attach one end of said additional connections to said vertical shafts at the other end of said car and means to attach the other end of said additional connections to said rock shafts, sand boxes, valves corresponding in number to the number of said rock shafts, means to conduct sand from said boxes to said valves, connections between said valves and said rock shafts, and directing pipes from said valves; all arranged so that the turning of a given number of said vertical shafts turns a determined number of said rock shafts to actuate the valves connected thereto.

3. A car, a plurality of vertical shafts at one end of said car, and wheels on said

- shafts, at the lower ends thereof, to turn therewith, a plurality of rock shafts and arms on said rock shafts, in combination with longitudinally movable connections, 5 said connections comprising ends adapted to extend around said wheels, rods, and additional ends of flexible material respectively attached to said arms, sand boxes, valves corresponding in number with the number 10 of said rock shafts, means to conduct sand from said boxes to said valves, additional arms on said rock shafts, links connecting said additional arms to said valves, and directing pipes from said valves.
- 15 4. A car, a plurality of vertical shafts at the ends of said car, wheels on said shafts, a plurality of rock shafts, and arms on said rock shafts, in combination with longitudinally movable connections respectively comprising ends adapted to be wound around 20
- said wheels and ends adapted to be attached to said arms to permit movement of said arms without corresponding movement of the body of said connections, said body consisting of rods, sand boxes, valves corresponding in number with the number of 25 said rock shafts, means to conduct sand from said boxes to said valves, additional arms on said rock shafts, links connecting said additional arms to said valves, and directing pipes from said valves, all arranged so that the turning of a given number of 30 said vertical shafts at one end of said car turns a determined number of said rock shafts to actuate the valves linked thereto. 35

JAMES CASSIDY.

In the presence of—

GOLDEN WELLS RYAN,

CHARLES TURNER BROWN.
